Inventor:

UNITED STATES PATENT OFFICE.

WILLIAM HENRY WOOD, OF MAYLANDS, NEAR PERTH, WESTERN AUSTRALIA,
AUSTRALIA.

ANTINICOTIN TOBACCO-PIPE.

984,335.

Specification of Letters Patent. Patented Feb. 14, 1911.

Application filed October 22, 1909. Serial No. 524,029.

To all whom it may concern:

Be it known that I, WILLIAM HENRY Wood, a subject of the King of Great Britain, and residing at Maylands, near Perth, State of Western Australia, Commonwealth of Australia, have invented new and useful Improvements in Antinicotine Tobacco-Pipes, of which the following is a specification.

The object of this invention is to provide a tobacco pipe whose construction provides means whereby the nicotine or other injurious matter is caught and trapped and so prevented from entering the mouth of the smoker; furthermore the pipe is thereby maintained in a pure state so insuring a cool and sweet smoke.

My improved pipe comprises an intercep-
ter chamber for entrapping the nicotine,
said chamber being furnished at each end
with removable plugs in order to permit of
the chamber being blown or scoured clean
in a through and through manner.

The pipe further comprises a false or removable bowl which is held in the outer or bowl proper of the pipe said removable bowl being made of wood and used by way of a "refill" while the pipe except the mouth piece is preferably constructed of aluminium.

These features of construction will now be explained by the aid of the attached drawings in which—

Figure 1 gives a longitudinal section of the pipe, Fig. 2 being a vertical section on line x , x . Fig. 3 is a longitudinal sectional view of the hollow plug employed.

In these drawings a is the false or removable bowl which is held by its rim or over lap flange b within the outer bowl c of the pipe the latter bowl being made integral with the stem d as shown. This false bowl has the duct or teat e which communicates with the nicotine intercepting chamber f placed preferably as shown. This chamber is provided at its front end with the removable screw solid plug g and also at its front end with a similar but hollow plug j . Both these plugs screw into the nicotine chamber as shown. The hollow plug j is provided with a cap h having a vent m , said cap being partially rotatable on the plug and having the slot or cut out n for engagement with the fixed pin p of the plug. When it is desired to give the nicotine chamber a blow through

and without removing either of the plugs g or j , the cap is given a slight down turn so 55 bringing the vent m to its lowest point and thereby forming a free lead away for the ejected nicotine from its chamber and which ejection is effected by a blow through action made by the smoker's mouth. A reverse 60 turn of the cap brings the vent to the raised position so closing the lead away of the chamber f .

The mouthpiece 9 is made with a threaded ferrule $9'$ which screws into the stem d while 65 a suitable cavity or passage as r is formed in the stem for communication with the nicotine chamber f and bowl a .

The chamber f may be cleaned out by the removal of both the screw plugs g and j or 70 by the vent m as above described.

What I claim as my invention and desire to secure by Letters Patent is:

1. A tobacco pipe provided with a nicotine intercepting chamber having a plug fitted in one end thereof, said plug being provided with a rotatable cap formed with an ejecting vent for the nicotine. 75

2. A tobacco pipe provided with a nicotine intercepting chamber having a plug removably fitted in each end thereof, one of said plugs being provided with a rotatable cap formed with an ejecting vent for the nicotine. 80

3. A tobacco pipe provided with a nicotine intercepting chamber having a plug fitted in one end thereof, said plug being provided with an ejecting vent and a rotatable cap having a notch formed therein, and means provided upon said plug and extending into said notch for limiting the rotation of said cap. 85

4. A tobacco pipe provided with a nicotine intercepting chamber having a plug fitted in one end thereof, said plug being provided with a rotatable cap having a vent formed therein, and means provided upon said plug for limiting the rotation of said cap. 95

In testimony whereof I have signed my 100 name to this specification in the presence of two subscribing witnesses.

WILLIAM HENRY WOOD.
